UNITED STATES PATENT OFFICE.

JULIUS B. WANTZ, OF OAK PARK, ILLINOIS, ASSIGNOR TO VICTOR X-RAY CORPORATION, OF CHICAGO, ILLINOIS, A CORPORATION OF NEW YORK.

STEREOSCOPE.

Application filed October 16, 1924. Serial No. 743,958.

The present invention relates to stereoscopes and has particularly to do with one adapted for use to view both raygraphs and X-ray negatives.

5 It is among the objects of the invention to provide a device which will serve with equal facility with respect to both types of X-ray photographs, to design means for the distribution of the illumination employed 10 in conjunction with the examination of such raygraphs and X-ray films that such illumination will be dispersed in substantially the same manner as the rays from the X-ray tube were distributed in procuring the pictures under inspection, and to properly ventilate such an apparatus to prevent overheating of negatives no matter how long they may be disposed therein in the course of 15 study.

20 These, and such other objects as may hereinafter appear, are attained by the novel construction, combination, and arrangement of the novel apparatus illustrated in the accompanying two sheets of drawings, hereinafter made a part of this specification, and in which:—

Figure 1 is an elevation of a complete device embodying the invention herein described;

25 Figure 2 is an elevation of one of the light boxes employed in said device;

Figure 3 is a top view of said box;

Figure 4 is a front elevation thereof;

30 Figure 5 is a detail in elevation of a modified form of the device; and

Figure 6 is a vertical section of the tube stand on the line 6—6 of Figure 1, a fractional portion of such stand only being illustrated.

35 Like reference characters are used to designate similar parts in the drawings and in the disclosure of the invention herein-after made.

Reference should be had to Figure 1. 40 Upon a base 10 which may comprise several members joined together or which may be integrally formed, are disposed legs 11, adapted to spread outwardly for the purpose of supporting the device. At the outward extremity of one or all of legs 11 may be a device 12 for facilitating levelling the apparatus upon an uneven floor surface.

45 Secured to the base 10 is a standard 13 comprising a hollow vertical tube at the top 50 of which is secured a locking collar 14 hav-

ing the usual locking unit. Within the standard 13 is disposed a second standard 15, hereinafter called the inside standard, which is hollow (see Figure 6) and in which is disposed a coil spring 16, the top end of 55 which spring abuts the wall of inside standard 15 at its top. The bottom end of said spring 16 is seated upon the wall at the bottom of standard 13. Said spring 16 is for the single purpose of bearing a portion of 60 the weight of the apparatus disposed upon the base 10 so that said apparatus may be readily moved upwardly or downwardly from a normal balanced position in order to adjust the apparatus to an operator who, 65 according to his personal whims, may prefer to stand up or to sit down while examining negatives or raygraphs. Locking collar 14 secures the apparatus in any adjusted position desired. Ordinarily the balanced position is intermediate the levels occupied by the device when being used by a person of normal stature in standing position and when seated.

70 Projecting outwardly from standard 15 are two members 17 comprising arms or brackets whereby to provide a track frame, track members 18 being secured thereto in parallel relation. Upon said tracks 18 and at opposite ends thereof are two movable 75 carriages 19, one designated a right hand carriage and the other a left hand carriage. Said carriages are the same except one is the reverse of the other.

75 Said carriages 19 are adapted to be concurrently and equally moved toward and away from the center of the apparatus, which center rests in a line projected upwardly from the axis of standard 15, by an apparatus comprising cables and pulleys not 80 here shown but common to the art. In this way X-ray pictures may be placed away from the eye a distance equal to the distance from the X-ray tube to said pictures in order that the true dimensions and proportions of 85 the photographed objects may be visualized. A scale of distances may be provided for the convenience of the operator.

85 For controlling the strength of the light in the boxes hereinafter to be described, a 90 rheostat 20 having an operating handle 21 is disposed upon the arms 17 beneath tracks 18.

95 At the center of the apparatus and disposed upon a base 22 secured to tracks 18 is a standard supporting a member 23, pro-

100

105

110

- vided with means for angular adjustment (designated 24) and tilting adjustment (designated 25) of its upper section 26, upon which last mentioned section 26 is disposed 5 a pair of mirrors 27, geared to operate conjointly when the angular adjustment of one or the other is changed. At the top of said section 26 is a cross arm 28 from the ends of which depend pivotally mounted shields 10 or wings 29 of opaque material. Said shields or blinds 29 provide means for avoiding or shutting off the undesirable effects of the direct or reflected light produced by the illuminating apparatus which will shortly 15 hereinafter be disclosed, while the adjustability of the mirrors 27 permits the operator to view the X-ray images in a convenient and correct relation to the object from which taken.
- 20 Upon each of the carriages 19 is a base 30 which provides a support for a box 31 of a generally truncated pyramid configuration or form. Said box 31 at its back end is provided with a centrally disposed 25 lamp socket 32, in which a bulb 33 projecting horizontally and inwardly of said box is disposed. The axis of said lamp 33 coincides with the axis or center line of box 31, and ordinarily and preferably a lamp 30 having a point or ring filament concentrating the light rays is employed.
- At the front end of said box 31 is a frame 34 in which is included a translucent glass pane 35. Upon the top of said frame 35 is a roller shade 36 having a guide rod 37 at the side thereof, said shade 36 having an angular guide member 37^a, one section of which is aligned with the free end of the shade 36 while the other section forms 40 a sliding sleeve about said rod 37. A second roller shade 38 is disposed at one side of box 31 and is provided with a guide rod 39 across the top of said box 31, an angular guide member 39^a, similar to member 37^a cooperating with said shade 38 and rod 39 to keep said shade in proper alignment. A channel may be arranged in frame 34 at the bottom of glass 35 to support plates, films or raygraphs as the case may 45 be. The curtains 36 and 38 support such X-ray photographs at two of their other edges and exclude light from passing to the side of said image reproductions. It is usual to dispose the fourth side of such pictures at the edge of box 31 opposite roller shade 38 or adjacent rod 37. A picture held by said shades can not be accidentally displaced.
- Between the frame 34 and box 31 at the 50 top and bottom thereof, it is desirable to provide air slots, such slots being clearly visible in Figure 3 where they are designated 40. In order to provide such slots 40, it is customary to secure the box 31 at 55 its top and bottom by fingers 40^a projecting rearwardly from the frame 34. A shade or canopy not shown may be arranged at the top and bottom of frame 34 for arresting light rays escaping through slots 40 but these should be sufficiently removed from 60 said slots 40 so as not to prevent a free circulation of air therethrough.
- Secured to the upper section of frame 34 is an arm 41, generally bent, and at the end of which is disposed a reflector 41^a 75 having its open side toward and at an angle to the front of box 31, the reflecting surface of said member 41^a being adapted to concentrate the major portion of the light rays emanating from a bulb 42 disposed in 80 a socket upon said arm 41 and surrounded by reflector 41^a at the most central section of a raygraph held upon frame member 34.
- In Figure 4, a diagrammatic representation of light distribution in the apparatus 85 is shown. Whether the bulb 33 is lighted as it is in the case of films or plates, or the bulb 42 is used as is done when a raygraph is disposed at the front of the box 31 and upon glass 35, the most intense light produced is directed toward the center of the front of said box 31 with the intensity of such light decreasing as the edges of frame 34 are approached, as is indicated in said 90 Figure 4.
- 95 This distribution of light is adopted because in the production of X-ray pictures, whether they be films, plates or raygraphs, (a raygraph being a direct X-ray picture upon a sensitized photographic paper), the most intense X-rays affect the center of the film, plate or raygraph and that part of the object photographed upon the center of the film is nearest the X-ray bulb and hence, most contrasted. The intensity of the X-ray effects decreases as the margins of the film or raygraph are approached, for reasons quite manifest to any one skilled in X-ray photography.
- In the manner herein described, the light 100 upon the film or raygraph held in this device is made to correspond with the intensity of the X-ray illumination used in making the pictures, and a lighting of the film, plate or raygraph is obtained identical 105 with or substantially identical with the distribution of the penetrating and photographing rays from the X-ray tube.
- 110 In Figure 5, a modified form of the device is shown. Upon a member 26^a, which corresponds to member 26 in Figure 1, a tunneled member 50 is shown. This comprises two truncated cone sections joined at their smallest radii at which point and within 115 said sections a socket 51 is mounted. Within the socket 51 and vertically disposed is a lamp 52, the rays of which are adapted to proceed outwardly from the open ends of said tunnel 50 to illuminate raygraphs held 120 in the boxes 31 at the opposite ends of track 130

18 in Figure 1. The advantage of this construction is the elimination of the two separated lamp brackets 41, and the obtaining of necessary illumination through the source of a single lamp rather than two lamps as in the other form of device illustrated. Naturally, the light distribution upon the two raygraphs under inspection in this device is equal while it may be uneven in the form of the invention first described because of a difference in the lighting effect of the two globes employed.

The heat generated in box 31 by bulb 33 has a tendency to heat the glass 35 and the film or plate thereupon secured. By placing the slots 40 at the top and bottom of box 31 adjacent pane 35, ventilation is secured. A current or film of constantly changing air is drawn upwardly through the said slots 40 vertically across the back surface of said pane 35 which is in this manner kept cool.

Rheostat 20 controls either the bulbs 33 or bulbs 42. Variability in said lights is essential for the purpose of securing the best reading light for each particular image reproduction. The most effective light adjustment can only be fixed concurrently with the examination of each reproduction. It is advantageous to control each set of lights from a single rheostat for it makes it unnecessary for the operator to learn new movements.

I claim:—

1. A stereoscope comprising the combination of a frame, means upon said frame for holding a photographic reproduction for examination, a point source of illumination at the rear thereof, and reflector means in association with said source of illumination and adapted to distribute its light in a manner substantially uniform with the distribution of the X-light used in exposing the reproduction held in said stereoscope.

2. In combination in a stereoscope, a frame, means upon said frame for holding photographic reproductions, sources of illumination carried by said frame for illuminating said reproductions, and an extensible stand for said stereoscope comprising a support adapted to secure said frame in a horizontally rotatable position and having as a part thereof a member adapted to urge said support into extended position.

3. In combination with a stereoscope, boxes having faces for holding photographic reproductions, a source of illumination for said reproductions, a frame for said boxes, and a stand for said frame, said stand comprising an adjustable columnar support having relatively adjustable sections and providing means for horizontal rotatable movement, said sections having means adapted to normally urge them into extended position.

4. In combination with a stereoscope, a box having a face and means for holding a photographic reproduction thereagainst, a point source of illumination at the center and back of said box, and an external source of illumination comprising a light, a bracket, and a reflector affixed thereto, said reflector having reflecting surfaces for distributing the light from said external source upon said face in substantially the same manner as the rays from said internal light are distributed.

5. A stereoscope comprising means for holding photographic reproductions, a source of illumination for said reproductions, and a support of relatively adjustable sections, admitting of unitary horizontal rotary movement of said means for holding said reproductions and being adjustable to raise and lower the plane of such horizontal movement, said sections having an intermediate spring member adapted to urge them into extended position.
